Primary Examiner — T Chase Nelson*Assistant Examiner* — Kelly L Gross*(74) Attorney, Agent, or Firm* — Thomas A. O'Rourke; James Bongiorno**CLAIM**

The ornamental design for an vein imager and cradle in combination, as shown and described.

DESCRIPTION

FIG. 1 is a front view of an vein imager and cradle in combination showing the new design.

FIG. 2 is a first perspective view thereof;

FIG. 3 is a second perspective view thereof;

FIG. 4 is a left side view thereof;

FIG. 5 is a rear view thereof;

FIG. 6 is a right side view thereof; and,

FIG. 7 is a top view thereof.

The broken lines shown in the drawings depict portions of the vein imager and cradle in combination that form no part of the claimed design.
